UNITED STATES PATENT OFFICE

147,987

DESIGN FOR A LINK CHAIN FOR A BRACELET OR SIMILAR ARTICLE

Jacob L. Pessel, New York, N. Y., and Frank Slug, Paterson, N. J.

Application June 25, 1946, Serial No. 131,018
Term of patent 3½ years

(Cl. D45—4)

To all whom it may concern:

Be it known that we, Jacob L. Pessel and Frank Slug, both citizens of the United States of America and residents respectively of New York city, in the county of the Bronx and State of New York, and of Paterson, in the county of Passaic and State of New Jersey, have invented a new, original, and ornamental Design for a Link Chain for a Bracelet or Similar Article, of which the following is a specification, reference being had to the accompanying drawing, forming a part thereof.

Fig. 1 is a plan view of a link chain for a bracelet or similar article, showing our new design.

Fig. 2 is a side view thereof.

Fig. 3 is a plan view of one of the elements forming the link chain.

Fig. 4 is a side view of the element shown in Fig. 3.

Figs. 5 and 6 are respectively bottom and top views of the element shown in Fig. 3.

The dominant feature of the design resides in

the portions shown in full lines, the elements being continuous throughout the length of the chain as indicated by the broken line disclosure in Figs. 1 and 2.

We claim:

The ornamental design for a link chain for a bracelet or similar article, substantially as shown and described.

JACOB L. PESSEL.
FRANK SLUG.
